NORMAN ELMER RANDALL, OF SHANNOCK, RHODE ISLAND, ASSIGNOR TO COLUMBIA
NARROW FABRIC COMPANY, OF SHANNOCK, RHODE ISLAND, A VOLUNTARY ASSO-CIATION OF RHODE ISLAND

DESIGN FOR A TEXTILE FABRIC

Application filed July 3, 1930. Serial No. 36,274. Term of patent 3½ years.

To all whom it may concern:

Be it known that I, NORMAN E. RANDALL, a citizen of the United States of America, residing at Shannock, county of Washington, State of Rhode Island, have invented a new, original, and ornamental Design for a Textile Fabric, of which the following is a specification, reference being had to the accompanying drawing, forming a part thereof.

The figure is a face view of a textile fabric, showing my new design.

I claim:

The ornamental design for a textile fabric, substantially as shown.

NORMAN ELMER RANDALL.
